UNITED STATES PATENT OFFICE

93,736

DESIGN FOR AN AIR-COOLED PENHOLDER

William J. Riddel, Brattleboro, Vt., assignor to
C. E. Bradley Corporation, Brattleboro, Vt., a
corporation of Vermont

Application July 6, 1934, Serial No. 52,474

Term of patent 7 years

To all whom it may concern:

Be it known that I, WILLIAM J. RIDDEL, a citizen of the United States, residing at Brattleboro, in the county of Windham, and State of Vermont, have invented a new, original, and ornamental Design for Air-Cooled Penholders, of which the following is a specification, reference being had to the accompanying drawing, forming part thereof.

Fig. 1 is a perspective view of my new design for a pen holder.

Fig. 2 is an enlarged fragmentary view in detail.
I claim:

The ornamental design for an air-cooled penholder as shown and described.

In testimony whereof I affix my signature.

WILLIAM J. RIDDEL.
